UNITED STATES PATENT OFFICE.

CHARLES E. MERRIFIELD, OF INDIANAPOLIS, INDIANA.

STRAW-STACKING MACHINE.

SPECIFICATION forming part of Letters Patent No. 274,134, dated March 20, 1883.

Application filed November 20, 1882. (No model.)

To all whom it may concern:

Be it known that I, CHARLES E. MERRIFIELD, a citizen of the United States, residing at Indianapolis, in the county of Marion 5 and State of Indiana, have invented certain new and useful Improvements in Straw-Stacking Machines, of which the following is a specification.

My invention relates to an improvement in straw-stacking machines operated in conjunction with a thrashing and separating machine.

The object of my invention is to provide a straw-stacking machine which is easily operated, and with less risk of breaking than the 15 machines now in use, and which can be folded more compactly and with less risk of springing the working parts when ready for transportation. I attain this object by the mechanism illustrated in the accompanying drawings, in which—

Figure 1 is a perspective view of the entire machine ready for operation. Fig. 2 is a vertical longitudinal section, through turn-table and its immediate connections, on line $x-x$ on 25 Fig. 3. Fig. 3 is a top view, showing the turn-table and the manner of transmitting the power.

The same letters refer to the same or corresponding parts throughout the several views.

30 The derrick C is operated on truck A at the front of the straw-stacker. To one of the spars, c, is secured the windlass D. From it the cord d runs up through guide E to standing pulley E', then down through running pulley E², and up to staple or fastening e, where it is secured. The staple or fastening e and pulley E' can be secured to the cross-bar, as shown, or to the spars of the derrick; but if fastened to said spars, staple e must be secured 40 to a point on one spar just as high as the standing-pulley E' on the other spar.

The driving-belt H from the thrashing-machine, or the like, operates pulleys h and h' on horizontal shaft s. Pulley h' on shaft s operates pulleys h² and h³ on vertical shaft m by a belt. Pulley h³ on shaft m operates pulleys g' and g on horizontal shaft s' by a belt. Pulley g on shaft s' operates pulley g² on the horizontal shaft s² by a belt; and shaft s² operates 45 the straw-stacker. In place of pulley h' on horizontal shaft s, pulleys h² and h³ on vertical shaft m, and pulley g' on horizontal shaft s',

with their connecting-belts, chain-pulleys and chains can be used.

The turn-table J is supported by frame or 55 standards B B, which are hinged or pivoted to the carriage A, in order to allow said standards to be folded down during transportation, the standards being kept in an erect position during the operation of the machine 60 by uprights and clamps. The turn-table J is formed of stationary wheel I and revolving wheel I', and these are held in their relative position to each other by clamps R R, secured to wheel I'. 65

On the under side of wheel I are secured socket-plates n n. One end of each of the braces N N are inserted into sockets in plates n n. The other ends are notched to fit onto cross-rail of truck. The wheel I of turn-table 70 is hinged to standards B B by hinges i i.

By the use of standing pulley E' and running-pulley E², in connection with windlass D, the power is nearly doubled. By the manner of transmitting the power from the thrashing-machine or the like I dispense with all beveled gearing or cog-wheels. By hinging the turn-table J to standards B B the turn-table will lie upon the platform of the truck, and relieves it from the weight of the derrick 80 or stacker during transportation. By the bracing of turn-table J with braces N N the turn-table becomes more rigid and the operating of it correspondingly easier, and the wear and tear of machinery during operation 85 greatly diminished. By the clamps R R the wheels I and I' are held in their places and the separating of them during operation or transportation prevented.

What I claim, and desire to secure by Letters Patent, is—

The combination, in a turn-table, of pivoted supports B B, hinges i i, wheels I' and I, clamps R R, socket-plates n n, and braces N N, substantially as described, and for the purpose set forth.

In testimony whereof I have signed my name to this specification in the presence of two subscribing witnesses.

CHARLES E. MERRIFIELD.
